BOILER

Oscar F. Noss, West Englewood, N. J., and John W. Lockett, Oswego, N. Y., assignors to Fitz-gibbons Boiler Company, Inc., New York, N. Y., a corporation of New York

Application December 21, 1933, Serial No. 703,396

3 Claims. (Cl. 110—97)

The present invention relates to boilers, heat exchangers, and the like and has for an object to provide a boiler of the fire tube type having a high thermal efficiency.

5 The invention has been developed in connection with the production of an oil burning boiler designed more particularly for the heating of residences, and for the purposes of disclosure of the principles of the invention such a boiler will 10 be more particularly described. It will be understood, however, that the particular description is illustrative merely and is not intended as defining the limits of the invention.

In boilers generally and especially in oil burning boilers it is highly desirable that the draft effective in the combustion chamber and in the boiler tubes should be as nearly constant as possible.

20 In a single pass fire tube boiler the hot gases of combustion rise rapidly to the top of the combustion chamber and in response to chimney draft pass mainly through relatively few of the upper tubes while the flow through the lower tubes is much less.

25 This crowding of the combustion gases through the tubes of the upper rows creates a very uneven distribution throughout the bank of tubes and results in excessive speed of gases through the upper tubes leaving insufficient time of contact to 30 give up all useful heat with the result that the exit temperature of gases from the upper tubes is excessively high, often several hundred degrees above the temperature of the slower moving gases issuing from the lower tubes. This 35 obviously causes a low thermal efficiency.

Furthermore when combustion is not completed in the combustion chamber before the gases enter the tubes, the chilling of the gases below the ignition temperature by contact with the relatively 40 cold tube surfaces stops combustion and unburned products are deposited in the form of carbon and tar on the heating surfaces. This soot is one of the best heat insulators known, and when a relatively large part of the total volume of gases 45 passes through relatively few of the total number of tubes, an insulating coating of soot is built up rapidly in those few tubes with the result that the greater part of the combustion gases passes through the boiler with very low efficiency.

50 The inefficiency due to the unequal distribution of the hot gases is the more marked because the temperature of the water in the lower part of a boiler surrounding the lower rows of tubes is always lower than that of the water surrounding 55 the upper rows of tubes. Uneven distribution of

heat with consequent overheating of the upper tubes also increases the formation of scale thereon.

The present invention aims to equalize the chimney draft and the distribution of the flow of gas through the fire tubes. It aims further to provide a boiler in which the efficiency will be maintained without frequent cleaning by reducing the tendency to deposit soot in the tubes and by reducing the tendency to deposit scale from 10 the water upon the exterior of the tubes.

A further object is to provide an automatic vent operable in the event of explosions to release the pressure.

The invention stabilizes combustion conditions 15 by maintaining an automatically controlled constant draft and provides means for decreasing the draft through the upper tubes and for increasing the draft through the lower tubes. This is accomplished in the preferred embodiment illustrated 20 in the drawings by introducing a check valve which is balanced to open automatically when the draft in the chimney exceeds a predetermined limit and by providing in the smoke chamber a deflector hood having a somewhat restricted cross-sectional area over the outlets of 25 the uppermost fire tubes and with a gradually increasing cross-sectional area over the middle and lower tubes to provide a substantially uniform draft through all of the tubes.

30 The uniform draft and the uniform distribution of the gases throughout the bank of tubes accomplishes several advantageous results. In the first place the transfer of heat to the water of the boiler is more complete because of the 35 greater area of heat transferring surface with the consequent reduction of the temperature of the flue gases. In the second place the overheating of the uppermost tubes is eliminated with less deposit of soot within the tubes and less deposit 40 of scale on their outer surfaces. Furthermore, such soot as is deposited is distributed throughout the tubes and the efficiency of the boiler is maintained through a considerably longer period of use and less frequent cleaning is necessary. 45 There is also less strain on the boiler due to unequal heating and the circulation of water within the boiler is improved.

The nature and objects of the invention will be better understood from a description of an 50 illustrative embodiment for the purpose of which description reference should be had to the accompanying drawings forming a part hereof and in which—

Figure 1 is a diagrammatic partly cross-sec- 55

tional view of a horizontal oil burning fire tube boiler having a deflector plate and an automatic relief damper constructed in accordance with the invention.

- 5 Fig. 2 is a rear view of the same,
 Fig. 3 is a sectional view taken on the line 3—3 of Fig. 1,
 Fig. 4 is a rear view of the boiler with the rear door open to show the parts within,
 10 Fig. 5 is a sectional view taken on the line 5—5 of Fig. 2, and
 Fig. 6 is a detail sectional view of the rear door latch.

In the structure shown for purposes of illustration the boiler 5 comprises a combustion chamber 6 and fire tubes 7 extending horizontally from the combustion chamber to the smoke chamber 8, from the top of which a pipe 9 leads to the chimney. In accordance with the invention, means is provided for reducing the draft through the uppermost of the fire tubes in order to compensate for the tendency of the hot gases in the combustion chamber to rise to and pass through the uppermost tubes. By this means an even distribution of the gases through the tubes is obtained. In the particular arrangement shown a deflector hood 10 is suitably supported within the smoke chamber to form a substantially smoke tight seal along its sides and across its upper edge against the tube plate 11 into which the ends of the tubes are secured. The hood is made in two sections 12, 13, one slightly overlapping the other, suspended on hooks 14, 15 in the rear wall of the boiler, each section being small enough for removal through the rear door 16. The handles 17, 18 facilitate removal and replacement.

The cross-sectional area of the hood is relatively small at the top and increases downwardly in proportion such as to provide a substantially equal draft throughout the whole range of the bank of tubes. Ordinarily the hood may be correctly designed for a particular boiler so that it is unnecessary to make the hood of adjustable cross-section, as for example by pivoting the rear wall thereof to move inwardly. With this arrangement the draft from the lowermost tubes is substantially unimpeded by the deflector hood but that through the upper tubes is progressively more and more checked toward the top, thus compensating for the thermal effect whereby the hottest gases pass readily to the top of the combustion chamber and there create a draft inducing pressure. The form of hood shown in which the sides are closed is preferred to a mere flat plate because of the tendency in the case of the flat plate for the draft to be unduly increased through the tubes close to the outer edges of the plates. Obviously a single plate, flat or curved, could be designed to materially improve the draft condition often found in boilers of the horizontal fire tube type and if extended sufficiently toward the sides of the smoke chamber would give effective results.

65 The deflector hood is preferably placed sufficiently close to the outlets of the fire tubes so that, especially opposite the uppermost tubes, it substantially impedes the draft therethrough, although obviously there should be ample space for the passage of the gases.

70 The rear door of the smoke chamber is hinged at 19 and latched at 20. In order to permit release of pressure in the event of an explosion, as may happen when the oil burner is lighted, the latch stud 21 carries a spring 22 which holds the

latch 20 normally in inner securing position but permits movement outward in the event of excess pressure within the smoke box.

Uniformity of the effective draft at the combustion chamber is insured by the balanced check valve 25 mounted on ball bearings 26 in the door 16. The pivot axis is slightly off center whereby the larger area receives the air pressure of any back draft and causes immediate closing and is immediately opened by a suction greater than a predetermined amount. In order to hold the valve closed when the draft is within the predetermined limit a weight 27 is carried by the valve and projects inwardly therefrom. This weight may be adjustable as by making the weight to consist of a stud with lighter or heavier nuts but usually this is not necessary. The valve is made of cast aluminum for sensitiveness and furthermore the aluminum valve with the iron or steel mounting provides a relatively noiseless combination.

5 The door 16 is formed with a shield 30 projecting into the path of the hot combustion gases and having for part of its extent a lip 31 in order to deflect the gases from the check valve 25. Otherwise the gases escape through the valve when it opens in response to increased chimney draft. On one side the lip 31 is of reduced width to permit the check valve to open through quite a large arc, as indicated at 32. Closing movement of the check valve is limited by a lug 33 engaging the door.

10 The hole 35 is provided in the door 16 below the shield 30 to permit introduction of a thermostat to the point where the stack gases are hottest. Some engineers prefer to use such a thermostat as a safety device to shut off the oil burner if and when the gases get above a predetermined temperature.

15 It will be understood that the foregoing description is not intended as defining the limits of the invention for the principles involved may be variously applied and numerous embodiments of the invention may be developed without departing from the spirit of the appended claims.

20 We claim:

1. A fire tube boiler having, in combination, a combustion chamber, a smoke chamber, a bank of horizontal fire tubes leading from the combustion chamber to the smoke chamber and a deflector hood in the smoke chamber over the outlets of said fire tubes to deflect the gases downwardly and outwardly and to equalize the draft through the tubes, a balanced damper in the wall of the smoke chamber, and a shield for deflecting away from the damper the stream of gases issuing from below the deflector.

2. A fire tube boiler having, in combination, a combustion chamber, a smoke chamber, a bank of horizontal fire tubes leading from the combustion chamber to the smoke chamber, a door opening into the smoke chamber in line with the fire tubes, a removable deflector hood in the smoke chamber over the outlets of the fire tubes to equalize the draft through said tubes and arranged to deflect the gases downwardly and outwardly toward the door, a check damper consisting of a plate balanced on an eccentric diagonal pivot to open when the draft within the smoke chamber exceeds a predetermined limit, and a shield between the deflector hood and the check damper positioned to deflect the gases away from the check damper, substantially as described.

3. A fire tube boiler having, in combination, a

combustion chamber, a smoke chamber, a bank of horizontal fire tubes leading from the combustion chamber to the smoke chamber, a door opening into the smoke chamber in line with the fire tubes, a two part deflector hood in the smoke chamber over the outlets of the fire tubes to equalize the draft through said tubes and arranged to deflect the gases downwardly, hooks in the smoke chamber on which the deflector hood parts are removably suspended, a check

damper in the door consisting of a plate balanced on an eccentric diagonal pivot to open when the draft within the smoke chamber exceeds a predetermined limit, and a shield secured to the door between the deflector hood and the 5 check damper positioned to deflect the gases away from the check damper, substantially as described.
